UNITED STATES PATENT OFFICE.

ROBERT ASHE, OF SOMERVILLE, MASSACHUSETTS.

EDGE-BURNISHING MACHINE.

SPECIFICATION forming part of Letters Patent No. 364,156, dated May 31, 1887.

Application filed November 8, 1886. Serial No. 218,319. (No model.)

To all whom it may concern:

Be it known that I, ROBERT ASHE, of Somerville, in the county of Middlesex and State of Massachusetts, have invented a new and useful Improvement in Edge-Burnishing Machines, of which the following, taken in connection with the accompanying drawings, is a specification.

My invention relates to that class of edge-burnishing machines in which the boot or shoe to be operated upon is held and guided by the hands of the operator, the object being to so improve the construction of the operative parts that the jar or vibration usually resulting from the high rate of speed at which this class of machines are driven, and the consequent danger to the health of those who operate them, and the excessive wearing of the operative parts caused by such vibration are entirely overcome; also, to furnish an improved table-rest for supporting the hand or arm of the operator to assist him in holding the boot or shoe when any assistance is required. I attain these objects by the mechanism shown in the accompanying drawings, in which—

Figure 1 is an elevation showing all of the working parts of my machine, a part of the base being omitted as not needed in this case. Fig. 2 is a perspective view showing the burnishing-irons and their more immediate connecting parts. Fig. 3 is a vertical section showing details. Fig. 4 is a front elevation of my machine. Fig. 5 is a vertical section enlarged, showing in detail the parts connected to the burnishing-irons and their adjuncts; and Fig. 6 is a vertical section showing a method of connecting to one of the rocking shafts a circular burnishing-iron.

A, Figs. 1 and 4, shows the main post or standard, to which I attach my working machine.

A' A² A³ A⁴ A⁶ A⁷ C' C², Fig. 1, constitute the frame of the machine.

C, Fig. 1, represents the main shaft of the machine. To this shaft C, I attach the driving-pulley C³ and balance-wheel C⁴. To the end of the shaft C, by means of crank wrist-pins, I unite two working-links, H and C⁶, Fig. 4. These two working-links H and C⁶

serve to operate the two burnishing-irons H⁹ and D⁹.

The burnishing-iron D⁹ is operated as follows: The link C⁶, Fig. 4, is moved back and forth by its wrist-pin on the shaft C. The link C⁶ is connected to the lever C⁷, Figs. 1 and 4, and by the lever and arm to the clamping-hub C⁸, Figs. 1 and 5. The clamping-hub C⁸ is held firmly about rocking-shaft D, Figs. 5, 6, by a clamp screw at C¹⁰, so that any movement that is given to the link C⁶ by its crank wrist-pin on the main shaft C is communicated to the working-shaft D. The rear end of the shaft D is held in place by the part A' of the frame, which it enters, as shown in Fig. 5, and the body of the shaft is held centrally by the hollow shaft H⁵, Figs. 5 and 6, through which it extends.

To the front end of the shaft D, I attach at D' a block, D², Figs. 2, 3, 4, and 5. This block swings back and forth with the rocking of the shaft D, and has a projection or arm, D³, Figs. 2, 3, and 5, to which I attach, by means of a pivot, D⁴, the journal-piece D⁶, Fig. 2, the said journal-piece D⁶ having extending downward from it the tool-holder D⁸, D⁹ being the burnishing tool or "iron," which is held in place by a set-screw, D¹⁰, or other suitable means, Fig. 2. The arm D³ is formed with a clamp, as indicated at d, Fig. 2, for the purpose of holding the journal-pin D⁷, Fig. 3. The journal-piece D⁶ is also formed with a clamp, (see d', Fig. 2,) so that it shall have no looseness on the pin D⁷.

When the tool or iron D⁹ is not in use, it and its holder D⁸ may be turned on the journal-pin D⁷, so as to approach quite near to the other holder, H⁸, as indicated by dotted lines in Fig. 5. To secure the holder D⁸ and iron D⁹ in their desired positions, I have the following device:

An upwardly-projecting segment-arm, E, is attached to the journal-piece D⁶, Figs. 2 and 3. This segment-arm has a notch, E², and a projection, E⁴, which engage, as may be required, with the lever E¹, the lever E¹ being pivoted to the block D² by the pivot E⁶, Figs. 2, 3, and 4, and held down by the spring E⁸. When the iron or tool D⁹ is in use, the lever E¹ rests in the notch E² and holds the tool D⁹ out.

ready for use, as shown in Fig. 1; but when the tool D⁹ is not to be used the lever E⁴ is raised out of the notch E², and the tool D⁹ and its holder D⁸ are turned inward, (swinging on the journal-pin D⁷,) so that the lever E⁴ rests against the projection E⁷ and holds the holder and tool in the position indicated by the dotted lines in Fig. 5.

I will now describe my method of operating the second burnishing iron or tool, H⁹. On the main driving-shaft C, Fig. 1, I have a crank wrist-pin which operates the link H, Fig. 4, and the link in turn, acting through the pin H² and lever H³, which are connected to the hollow shaft H⁵ by the hub H⁴, Figs. 4 and 5, causing the hollow rocking shaft H⁵ to oscillate and to give a vibrating motion to the arm H⁷, tool-holder H⁸, and burnishing tool or iron H⁹. The burnishing tool or iron H⁹ is held in place by the set-screw H¹⁰, or other suitable means.

In Fig. 6 I have shown a modified form of one of my burnishing tools or irons. To use the modified—that is, the circular—iron K⁴, I remove the rocking shaft D of Fig. 5, and insert in its place the rocking shaft K⁷, Fig. 6. To the end of the shaft K⁷, I firmly attach the boss K. This boss K has screwed to it a snap-latch, K², the end of which engages with hub K³ of the circular burnishing iron K⁴ and holds it in place. K⁴ is a projection on the shaft K⁷, which enters into a socket made in the hub K³ and forces the circular iron K⁴ to vibrate with the shaft K⁷. The bed K⁵ of the burnishing tool or iron K⁴ is inclined, as shown, so that the operator may be enabled to press the shoe or boot edge against it and not require any other rest for hand or fingers.

By arranging the rocking shafts H⁵ and D^{4c} and the clamping-hubs H⁴ and C⁹ as I have shown in Fig. 5, I am enabled to adjust the said hubs to compensate for the wear of the connecting and operating parts.

B⁶, Fig. 1, is a table which serves for a rest 45 for the hands of the operator when such rest

is needed. The table is supported by the following-described means: A⁵, Figs. 1 and 4, is a projection extending from the standard A. Extending from A⁵, I have a large-headed bolt, B, the shank of which is held in place by the set-screw B'. Through the head of the bolt B is a horizontal bar, B², slides, said bar being held by a set-screw, B³. At the end of the bar B², I attach a hub, B⁴, and vertically in it is placed an adjustable rod, B⁵, held by the set-screw B⁶, Fig. 4. To the lower end of the rod B⁵, I attach an arm B⁸, Fig. 1, which supports the table B⁶ by screws B¹⁰ B¹⁰ and bosses B⁹ B⁹.

To prevent the table B⁶ from swinging around too far, I place a stud, b, on the arm B⁸ and a pin, b', in the rod B⁵. This device will allow the table to swing to the right against the standard A and out of the way of the operator, but will limit its motion to the left—that is, it will allow the table to swing out just far enough for use and no farther.

I claim—

1. In an edge-burnishing machine, the combination of the main shaft C, having upon it wrist-pins, the links H C⁶, levers H³ C⁷, and adjustable clamping-hubs C⁹ H⁴ with the rocking shaft D and hollow rocking shaft H⁵, all operating together substantially as described, and for the purpose set forth. 70

2. In an edge-burnishing machine, the combination of the rocking shaft D, the arm D², and journal-piece and tool-holder D⁶ D⁸ with the segment-piece E² and lever E⁴, all operating together substantially as described, and for the purpose set forth. 75

3. In an edge-setting machine, the combination of the bolt B, sliding bar B², and hub B⁴ with the adjustable rod B⁵, swinging arm B⁸, and table B⁶, all substantially as described, and for the purpose set forth. 80

ROBERT ASHE.
